(57) **CLAIM**

The ornamental design for a track rail for linear motion guide device, as shown and described.

DESCRIPTION

FIG. 1 is a perspective view of a track rail for linear motion guide device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken away symbols in the drawings indicate that any portion of the article beyond what is shown forms no part of the claimed design.
